HAIR CUTTING COMB

Warren M. Mansfield, Glendale, Calif., assignor
to Sta-Neet Corporation, Los Angeles, Calif., a
corporation of California

Application January 27, 1947, Serial No. 724,607

4 Claims. (Cl. 30—30)

1

This invention relates to a hair cutting comb adapted for trimming and thinning the hair, and pertains more particularly to such a device provided with an adjustable cutting blade of the "safety razor" type which is adjustable with respect to the comb teeth to different positions for use as a hair trimmer, hair thinner, or plain comb.

This application relates to the same general type of device as that covered in the application of Sanford E. A. Sanders, entitled "Hair cutting comb" filed June 8, 1946, Serial Number 675,375, and is distinguished therefrom in the character of the supporting means for the adjustable blade.

A particular object of this invention is to provide a device which may be fabricated at a low cost, is simple in operation, and effective in use.

A further object of the invention is to provide a hair cutting comb having an adjustable blade thereon cooperating with the comb teeth, in which the adjustable blade is adapted to be frictionally retained in any given position of adjustment.

The above and other objects of this invention will be more fully brought out in or will be apparent from the ensuing description of a preferred embodiment of the invention as illustrated in the accompanying drawings, in which:

Fig. 1 is a side elevation of a hair cutting comb of my invention;

Fig. 2 is a fragmentary longitudinal section thereof, on an enlarged scale, as taken on line 2—2 in Fig. 1;

Fig. 3 is a fragmentary partly-broken-away elevation of the central portion of the comb shown in Fig. 1, as taken on line 3—3 in Fig. 2; showing the cutting blade in one operative position;

Fig. 4 is a view corresponding to Fig. 3, with the cutting blade in an alternative operating position, and

Fig. 5 is a transverse section of the structure, as taken on line 5—5 in Fig. 1, on a scale intermediate that of Figs. 1 and 2.

Referring to the drawings, a comb body is indicated at 1, provided along one edge with a series of comb teeth 2, the central section 3 of which is intended to be employed in the function of "thinning" the hair, as hereinafter more particularly described. A second series of teeth 4 is preferably also provided along the opposite edge of the comb body 1, as at the longitudinally central section thereof, which teeth are intended to be employed as "trimming" teeth. The comb body is

2

provided with a longitudinally extending recess 5 at the position of the thinning section 3 of the teeth 2 and at the position of the trimming teeth 4, said recess being provided with a curved back wall 6. Shoulders 7 are provided to define the end walls for the recess 5, together with overlying shoulders 8 adjacent the end shoulders 7 cooperating therewith to define longitudinally spaced opposing slots 9 which extend generally parallel to the plane of the comb body 1 and transverse to the length of such body. The recess 5 is adapted to receive a cutting blade of the "safety razor" type, as shown at 10, which blade is preferably provided with a pair of longitudinally extending cutting edges 10a and 10b. The blade 10 is adapted to be retained within the recess 5 through the agency of a generally planar resiliently deformable slide member 11 which is preferably provided with projections or lug means 12 projecting from the plane of the member 11 and adapted to engage apertures 13 provided in the blade 10. The length of the slide member 11 is preferably such as to cause the end portions 14 thereof to slidably engage the end shoulders 7 of the recess 5, a minor clearance therebetween being shown in the enlarged scale view of Fig. 2, so as to bear upon said shoulders 7 to guide the member 11 in its transverse movement within the slots 9 and cause the cutting edges 10a and 10b to be restrained in relative parallelism with the length of the comb body 1 in all positions of adjustment of the blade 10 and slide 11 within the recess 5.

The structure is assembled by superimposing the slide member 11 upon a blade 10, fitting the projections 12 into the apertures 13 of the blade, bending the blade and slide member longitudinally into a shape consonant with the curved shape of the back wall 6 of the recess 5, and sliding the blade and slide member into the slots 9. The restoring forces resulting from the resilient deformation of the blade 10 and slide member 11 out of the normally plane shape will produce a frictional engagement of the blade 10 upon the back wall 6 of the recess 5, and a frictional engagement of the ends 14 of the slide member 11 upon the overlying shoulders 8 at the ends of the recess, tending to cause the assembled blade and slide member to be retained in any adjusted position thereof transversely of the comb body. The outer face of the slide member 11 may be provided with projections 16 to facilitate the frictional engagement of the slide member by the user, if desired.

The "thinning" comb teeth arranged in the

central section 3 adjacent the position of the recess 5 are shown as comprising a plurality of cooperating tooth pairs 17, the structure being slotted as at 18 between adjacent pairs to a position beyond the lower edge of the recess 5, as may be defined by aligned ledges 19 on the tooth pairs 17. This extension of the slots 18 beyond the ledges 19 is readily apparent from Figs. 3 and 5, from which it will be seen that the lower edge 10b of the blade 10 is available for contact with the hair gathered within the slots 18 while the intermediate portions of the blade at the position of the ledges 19 is guarded against contact with the portion of the hair which will enter the slots 20 between adjacent teeth of individual pairs. The comb body is preferably sloped away from the most inwardly end portion of the slots 18, as shown at 21, which facilitates the passage of the comb device through the hair and the engagement with the blade edge 10b with the hair portions disposed within the slots 18.

As shown in Figs. 3 and 4, the assembled slide member 11 and the blade 10 are adapted for a rather considerable lateral adjustment in position; in the position of Fig. 3 the blade edge 10a is available for a shaving operation, as in clearing the hair from the leg, for example, and in the position of Fig. 4 the cutting edge 10b is positioned in cooperation with the thinning teeth 17 while the cutting edge 10a is positioned to cooperate with the teeth 4 for a trimming operation, it being required to invert the comb body in use so that the respective cutting edges are drawn toward the hair to be cut in each case. With the cutting blade in the position of Fig. 3, the teeth 2 and 3 of the comb may be employed in a normal combing relation.

The projections 12 at the rearward face of the slide member 11 which are intended to engage the apertures 13 in the blade 10 are preferably of such length with respect to the thickness of the blade 10 as to project beyond the blade when the slide member is superimposed thereupon, which facilitates the placement of the blade upon the projections, and I may provide clearance recesses 23 in the back wall of the recess 5 in position to accommodate the projections 12 without interfering with the transverse adjustment of the blade with respect to the comb body.

The above specific description of a preferred embodiment of my device is given by way of illustration only, and I do not consider my invention as limited strictly thereto, but rather to the scope of the subjoined claims. For example, while I have shown the blade 10 as being disposed in a recess 5 which is located centrally of the length of the comb 1, it will be obvious that the blade and recess may be located nearer to or at one end of the comb, without departing from my concept. Furthermore, while I have described my preferred structure as utilizing a slide member such as shown at 11 to cover the blade 10, it will be appreciated that the omission of this member is entirely feasible where the stiffness of the cutting blade is sufficient to produce a frictional engagement of the blade upon the bottom of the recess 5 and the shoulders 8 which is adequate to hold the blade in adjusted position in use. Where the slide is omitted, it may further be preferable to increase the curvature of the recess wall 6, and/or materially decrease the spacing of the shoulders 8 from the bottom of the recess 5 at its ends.

I claim:

1. A hair cutting comb, which comprises: an elongated generally planar comb body provided with a plurality of comb teeth along one edge thereof and an elongated recess in one side adjacent the position of at least some of said teeth, said recess being adapted to receive a thin metal blade of the "safety-razor" type with a cutting edge thereof disposed generally parallel to the length of said body, and said recess having a back wall of outwardly convex curvature in the direction of the length of said body, and said comb body having shoulder means at the longitudinal ends of said recess in spaced opposition to said back wall; and a resiliently deformable slide member of generally planar form adapted to slidably engage within said recess in superimposition upon such a blade upon deformation of such member and blade into curved shape consonant with the curvature of said back wall, and to be frictionally retained in said recess by engagement thereof by said shoulder means.

2. A construction as set forth in claim 1, said slide member being of shorter transverse dimension than the blade adapted to be received within said recess to thereby expose the cutting edge of said blade in use.

3. A construction as set forth in claim 2, said slide member being provided with lug means projecting from one face thereof and adapted to engage within apertures provided within such a blade and thereby position such blade relative to said slide member.

4. A hair cutting comb which comprises: an elongated generally planar comb body provided with a plurality of comb teeth along one edge thereof and an elongated recess in one face in spaced relation to the tips of said teeth throughout a portion of the length of said body; first shoulder means provided by said body to define the longitudinal ends of said recess; second shoulder means defined by said body at the longitudinal ends of said recess to define a pair of longitudinally spaced opposing slots extending generally parallel to the plane of said body transverse to the length thereof, and said recess having a back wall of outwardly convex curvature in the direction of the length of said body between the position of said slots, and being adapted to receive a thin metal blade of the double-edge "safety-razor" type with its cutting edges disposed generally parallel to the length of said body; and a resiliently deformable slide member of generally planar form adapted to be slidably disposed within said recess in superimposition upon such a blade, with the longitudinal ends of said member disposed within said slots in sliding engagement with said first shoulder means and in frictional engagement with said second shoulder means, upon deformation of said member and the blade into curved shape consonant with the curvature of said back wall.
